(57) **CLAIM**

The ornamental design for a quick coupling unit for piping as shown and described.

DESCRIPTION

1. Quick coupling unit for piping

1.1 : Perspective

1.2 : Another perspective view

1.3 : Front

1.4 : Top

1.5 : Left

1.6 : Right

1.7 : Exploded

The rear view has been omitted, since the rear view is the mirror image of the front view; the bottom view has been omitted, since the bottom view is identical to the top view.

1 Claim, 7 Drawing Sheets
